Attorney.

UNITED STATES PATENT OFFICE.

MAURICE K. BURGER, OF NEW YORK, N. Y.

NECKTIE.

SPECIFICATION forming part of Letters Patent No. 340,478, dated April 20, 1886.

Application filed July 23, 1885. Serial No. 172,370. (No model.)

To all whom it may concern:

Be it known that I, MAURICE K. BURGER, a citizen of the United States, and a resident of New York, in the county of New York and 5 State of New York, have invented certain new and useful Improvements in Neckties, of which the following is a specification.

My invention relates to neck-wear; and its primary object is to so construct a neck tie or 10 scarf that it may be easily and quickly adapted by the wearer, without any alteration in the structure itself, to accommodate itself to a standing or turn-down collar.

I have shown my invention in the accompanying drawings applied to the conventional neckscarf.

In my invention the usual supporting shield is employed, in connection with which I use a curved piece, which passes through the loop 20 at the top of the front pieces of the scarf and projects the same distance on each side of the said loop. Extending from the ends of this curved piece are the bands which are adapted to secure the scarf around the neck of the 25 wearer, which bands may be folded back on the ends of the curved piece, and secured in that position when the scarf is used with a turn-down collar.

The features of novelty for which I desire 30 protection by Letters Patent are pointed out in the claims at the end of this description.

In the accompanying drawings, which form a part of this specification, and in which like parts are indicated by like letters, Figure 1 35 represents a front elevation of a scarf embodying my improvements. Fig. 2 is a rear elevation of the same. Fig. 3 is a front elevation showing the ends of the bands which encircle the wearer's neck folded back of the scarf; 40 and Fig. 4 is a rear elevation of the same scarf, indicating the manner of folding and securing the neckbands against the back of the scarf.

Referring to the drawings, the letter A represents the front pieces of the scarf, which in 45 the structure shown cross each other, as indicated.

B represents the piece of scarf material which projects up above the top of the cross-pieces A, and is secured at the rear of the 50 scarf, in the form of a loop, to the rigid shield C, which latter device preserves the shape of the structure. The edges of the cross pieces A are also attached at a to the shield C.

Passing through the loop B is the curved piece E, which is formed integral with the 55 shield C, and when in position equal parts of said curved piece project from both sides of the loop, as shown. The bands D D', which encircle the neck of the wearer, are secured over the curved piece E, as shown. One of 60 these bands may be provided with a buckle, d, as shown, for the purpose of securing the two ends together and adjusting the bands around the wearer's neck.

When the scarf is used with a standing collar, the bands D D' encircle the wearer's neck in the usual manner, and the curved piece E being rigid, but flexible enough to enable it to conform to the collar upon the wearer's neck, prevents the bands from twisting and 70 assuming an untidy appearance where they fit over the loop B.

When the scarf is to be used with a turn-down collar, the bands D D' are folded back against the curved piece E, as shown in Fig. 75 4 of the drawings, and to hold them in this position is the function of the elastic cord c, which is secured to the shield C in the manner shown, being tacked in the center, so that the bands are held separated.

The cord b, which is in one piece with the cord c, as shown, is provided with a ring, e, such as usually employed for affixing a bow to the collar-button. When the bands D D' are folded back on the curved piece E, their 85 ends are passed beneath the cord c as well as between the cord b, so that double security is provided against their getting out of position when once adjusted, as explained.

It will be observed that when the scarf is used 90 with a turn-down collar, the ends of the curved piece E fit under the collar, and thus keep the scarf well adjusted to the shape of the neck of the wearer, it being secured against accidental displacement by the ring e, fitting over the collar-button, as already explained. A neat and accurate adjustment of the scarf to the wearer's neck is also insured when any of the usual standing collars are worn with a necktie 95 embodying my improvements.

Having thus described my invention, what I claim as new, and desire to secure by Letters Patent, is—

1. A neck tie or scarf provided with a flexible curved piece, as E, the ends whereof project beyond the sides of the scarf, for the pur- 105

pose explained, each of said ends being provided with a band, whereby the scarf may be secured in position, substantially as set forth.

2. A neck tie or scarf comprising a supporting-shield, a loop, B, flexible curved piece E, whose ends project from the sides of said loop and beyond the sides of the scarf, and bands permanently secured to the ends of said curved piece E, substantially as set forth.

3. A neck tie or scarf provided with a curved piece, as E, whose ends project beyond the

sides of the scarf and are provided with bands, as shown, and the cord e, whereby said bands are held against the back of the shield of the scarf, substantially as set forth.

Signed at New York, in the county of New York and State of New York, this 20th day of July, A. D. 1885.

MAURICE K. BURGER.
